(57) **CLAIM**

The ornamental design for a golf ball, as shown and described.

DESCRIPTION

FIG. 1 is a front perspective view of a golf ball according to our new design.

FIG. 2 is a first side view of the golf ball of FIG. 1.

FIG. 3 is a second side view of the golf ball of FIG. 1.

FIG. 4 is a front view of the golf ball of FIG. 1.

FIG. 5 is a back view of the golf ball of FIG. 1.

FIG. 6 is a top view of the golf ball of FIG. 1; and, FIG. 7 is a bottom view of the golf ball of FIG. 1.

The broken lines in the drawings illustrate environment and form no part of the claimed design.
